The ornamental design of a wireless short hop module for a subterranean bottom hole assembly, as shown and described.

DESCRIPTION

FIG. 1 is a perspective view of a wireless short hop module for a subterranean bottom hole assembly according to our design.

FIG. 2 is an enlargement of FIG. 1 as shown on FIG. 1.

FIG. 3 is an enlargement of FIG. 1 as shown on FIG. 1.

FIG. 4 is an enlargement of FIG. 1 as shown on FIG. 1.

FIG. 5 is an enlargement of FIG. 1 as shown on FIG. 1.

FIG. 6 is an enlargement of FIG. 1 as shown on FIG. 1.

FIG. 7 is a front elevational view of the wireless short hop module for a subterranean bottom hole assembly.

FIG. 8 is an enlargement of FIG. 7 as shown on FIG. 7.

FIG. 9 is an enlargement of FIG. 7 as shown on FIG. 7.

FIG. 10 is an enlargement of FIG. 7 as shown on FIG. 7.

FIG. 11 is an enlargement of FIG. 7 as shown on FIG. 7.

FIG. 12 is an enlargement of FIG. 7 as shown on FIG. 7.

FIG. 13 is a rear elevational view of the wireless short hop module for a subterranean bottom hole assembly.

FIG. 14 is an enlargement of FIG. 13 as shown on FIG. 13.

FIG. 15 is an enlargement of FIG. 13 as shown on FIG. 13.

FIG. 16 is an enlargement of FIG. 13 as shown on FIG. 13.

FIG. 17 is an enlargement of FIG. 13 as shown on FIG. 13.

FIG. 18 is an enlargement of FIG. 13 as shown on FIG. 13.

FIG. 19 is a left side elevational view of the wireless short hop module for a subterranean bottom hole assembly.

FIG. 20 is an enlargement of FIG. 19 as shown on FIG. 19.

FIG. 21 is an enlargement of FIG. 19 as shown on FIG. 19.

FIG. 22 is an enlargement of FIG. 19 as shown on FIG. 19.

FIG. 23 is an enlargement of FIG. 19 as shown on FIG. 19.

FIG. 24 is an enlargement of FIG. 19 as shown on FIG. 19.

FIG. 25 is a right side elevational view of the wireless short hop module for a subterranean bottom hole assembly.

FIG. 26 is an enlargement of FIG. 25 as shown on FIG. 25.

FIG. 27 is an enlargement of FIG. 25 as shown on FIG. 25.

(Continued)

FIG. 28 is an enlargement of FIG. 25 as shown on FIG. 25.
 FIG. 29 is an enlargement of FIG. 25 as shown on FIG. 25.
 FIG. 30 is an enlargement of FIG. 25 as shown on FIG. 25.
 FIG. 31 is a top view of the wireless short hop module for a subterranean bottom hole assembly.
 FIG. 32 is a bottom view of the wireless short hop module for a subterranean bottom hole assembly.
 FIG. 33 is a section view as shown on FIG. 31.
 FIG. 34 is an enlargement of FIG. 33 as shown on FIG. 33.
 FIG. 35 is an enlargement of FIG. 33 as shown on FIG. 33.
 FIG. 36 is an enlargement of FIG. 33 as shown on FIG. 33.
 FIG. 37 is an enlargement of FIG. 33 as shown on FIG. 33; and,
 FIG. 38 is an enlargement of FIG. 33 as shown on FIG. 33. The dot-dash broken lines depict the limits of the enlarged views and form no part of the claimed design.
 The short, evenly-spaced broken lines on FIGS. 1, 4-7, 10-13, 16-19, 22-25, 28-33 and 37-38 depict portions of the article that form no part of the claimed design.
